UNITED STATES PATENT OFFICE.

WILLIAM M. KEPLER, OF CINCINNATI, OHIO.

IMPROVEMENT IN FIRE-PLACES.

Specification forming part of Letters Patent No. **142,241**, dated August 26, 1873; application filed May 7, 1873.

To all whom it may concern:

Be it known that I, WILLIAM M. KEPLER, of Cincinnati, Hamilton county, State of Ohio, have invented a certain new and useful Improvement in Fire-Places, of which the following is a specification:

My invention relates to the class of fire-places having air-heating chambers back of the fuel-chamber for the supply of heated air to assist in warming the room the fire is in, or the supply of heated air for conveyance to other compartments; and my invention consists, first, in a peculiar formation of the corrugated back plate of the fire-place which separates the fire-chamber from the air-heating chamber, by which a greater amount of heat is conducted into the air-heating chamber, and more complete combustion effected in the fuel-chamber, than has been found possible to attain with the old forms of corrugated fire-backs; second, in a peculiar construction of top plate for the heating-chamber, which not only serves to hold the corrugated fire-back in place, but enables the top plate to be reversed in position, so as to present the side exit-pipe for the hot air, either upon the right or left side of the fire-place.

Figure 1 is a vertical section of a fire-place embodying my invention. Fig. 2 is a perspective view of the corrugated fire-back with its reversible top plate.

A is the air-heating chamber, and B the fire-chamber. They are separated by the fire-chamber back C, which is of the following peculiar construction: It is formed with a series of corrugations horizontally arranged, each corrugation having a front face, c, to radiate heat directly into the room and into the air-heating chamber, and also a horizontally-located face, c', which acts to catch or arrest the rising gases from the fire, and form reverberating eddies in the corrugations to such extent that the fire-

back is effectively heated, the air in the air-chamber heated by direct horizontal heating-surface principally, and the combustion in the fire-chamber (by reason of the high temperature of the fire-back and the reverberatory action) materially perfected. The overhanging character of the fire-back C is preferred by me, as it affords, as shown, a favorable configuration for the arrangement of my peculiar form of corrugations. The top plate D of the air-heating chamber is provided at the side with the exit-pipe E for the conduction of hot air, and is constructed with grooved ends d d', to fit over the top edge of the fire-back, and hold the latter in place. The back end of the top plate is built in the brick-work, as shown. The plate D is grooved both at its front and back edge, as shown at d d', so that in setting up the fire-place either edge may be set in front over the top edge of the fire-back, in order to locate the pipe E on the side most favorable for the conveyance of the heated air from the fire-place. Pipe or flue F supplies the cold air for the heating-chamber A. The fire-back C has side flanges, to build into the brick-work of the fire-place, as shown at c" c'", Fig. 2.

I claim—

1. In an air-chambered fire-place, A B, constructed substantially as described, the corrugated fire-back C, when the corrugations are arranged horizontally, and formed by rising faces c and horizontal faces c', as and for the purpose described.
2. In combination with the fire-back C, the reversible grooved top plate D E d d', substantially as and for the purpose specified.

In testimony of which invention I hereunto set my hand.

WM. M. KEPLER.
